CLAMP

Frank C. Wallace, Los Angeles, Calif., assignor to
 Monogram Manufacturing Co., Los Angeles,
 Calif., a corporation of California

Application November 21, 1941, Serial No. 419,941

10 Claims.

(Cl. 85—5)

This invention has to do with clamps and relates more particularly to clamps used as temporary means for clamping perforated sheets together in superposed relation, with their perforations in register, while awaiting the application of permanent rivets. This invention involves improvements upon those inventions disclosed and claimed in my copending applications Serial Number 387,198, filed April 7, 1941, and Serial Number 408,085, filed August 23, 1941.

A well known difficulty with conventional clamps is that they scratch and mar the surface of the sheets to which they are applied, and this is particularly true of their use in riveting the sheets going to make up airplane fuselages, since those sheets are relatively softer than the steel of which the clamp body is made. Thus in applying and removing the clamp the exterior surface of the sheet around the rivet hole is injured. It is therefore one of the principal objects of this invention to overcome this serious shortcoming of the prior art by providing a clamp which embodies simple and effective means for protecting the clamped surface of the sheet.

Another object contemplated is the provision of a clamp embodying efficient means for mounting such a protective member upon the clamp body.

Another object is the provision of a clamp embodying a retaining or clamping member which is particularly conducive to facility and economy of manufacture.

Additional objects and advantages are inherent in my invention and how those as well as the foregoing are accomplished will become apparent from the following detailed description of a presently preferred embodiment thereof, for which purpose I shall refer to the accompanying drawing, in which:

Fig. 1 is a longitudinal sectional view of my clamp showing the position which its parts occupy when the clamp is being applied;

Figs. 2 and 3 are elevational views showing the clamp in different positions of use, a part of the spring being broken away in Fig. 3 for illustrative purposes;

Fig. 4 is a longitudinal section on line 4—4 of Fig. 2;

Fig. 5 is a cross-section on line 5—5 of Fig. 1;

Fig. 6 is a cross-section on line 6—6 of Fig. 1; and

Fig. 7 is a sectional view similar to Fig. 6 but showing a variational form.

In the drawing, I show superposed sheets S having perforations P. The numeral 5 design-

nates the body or housing of my clamp, which is cylindric in form and has an end wall 6 provided with a central opening 7. An annular recess 8 provides means for mounting the body in a clamp applying tool, not shown.

A retaining member generally designated by the numeral 10 is reciprocally mounted in the body and includes a stem 15, headed at 16, having a reduced inner end 17 and an annular groove 18 intermediate its ends. A pair of diametrically expandable retaining fingers 19 have oppositely disposed inner end portions 20 disposed at right angles to the longitudinal axis of the stem 15 and bifurcated to embrace the stem circumferentially of the groove 18. Fingers 19 are held in such assembly by the encircling coil spring 25 which seats at its outer end against head 16 and at its inner end against end wall 6. This construction of the retaining member is highly advantageous from the standpoint of facility and economy of manufacture. These retaining members are usually made by the swaging process and it is difficult to form an integral member having a rounded end portion 15, 16 and the forked outer sheet engaging end; also they must be made to fit perforations of extremely small diameters such as of the order of one-eighth inch or less, which further increase the manufacturing difficulties. In my described structure, however, the fingers 19 are formed separately from the stem portion and may be readily made, assembled and then held in assembly simply by means of the surrounding spring. The outer ends 26 of the fingers are protractable and retractable 25 through openings 7 and have enlarged outer ends 27 providing shoulders 28 which engage the sheet S farthest from the clamp during the clamping operation to be described.

Body 5 has an annular groove 30 at its inner end into which the peripheral portion of an end cap 31 is crimped to securely hold the cap on the body. Cap 31 has a relatively large central opening 32 through which an insulating member 35 projects, said insulator having an annular flange 35a confined by cap 31 to prevent outward escape of the insulator through opening 32, and a spherical, smooth, non-abrasive outer surface 35b adapted to bear against the outer sheet S when the device is in clamping position. A central hole 35c is provided through the insulator to slidably pass fingers 19. While, in the drawing, I have shown insulator 35 as being made of hard rubber, it should be understood that other suitable materials may be employed, the only requisite being that the material of which the insu-

lator is made shall be non-abrasive with respect to the sheet against which it is to bear. For instance, these clamp bodies are usually made of hard steel in order to withstand the considerable stresses to which they are subjected and, in using the clamps to fasten aluminum or similar sheets, abrasion and injury result unless some positive protective means is provided. In practice, I have found various well known plastics to be suitable for the material of the insulator.

A T-shaped spreader having a cross arm or anchor portion 40 and a central arm 40a is disposed between fingers 19, the anchor portion 40 being rotatably mounted in the circular recess 35d provided in the inner surface of the insulator. A guide ring 41 rests in recess 35d and surrounds the outer ends 26 of the fingers to prevent said fingers from spreading apart into wearing engagement with the insulator. The spreader is held against longitudinal movement between the end wall 6 of the body and the ring 41. Thus as the fingers 19 slide longitudinally over the sides of the spreader, they are diametrically expanded, but the spreader is free to rotate with the retaining member 10 to prevent twisting and injury to the retaining fingers during use of the clamp.

In operation, the body 5 is operated and applied by means of a clamp applying tool such, for instance, as shown in the copending application of Herman H. Helbush, Serial Number 411,879, filed September 22, 1941, and by means of this tool the retaining member is moved inwardly of the body against the pressure of spring 25 to protract fingers 19. The central arm 40a of the spreader being shorter than the fingers 19, when spring 25 is thus fully compressed, the fingers 19 project from the body a sufficient distance beyond the outer end of the spreader (as shown in Fig. 1) to enable the outer ends of the fingers to be compressed together to insert their enlarged ends 27 through registering perforations P in the sheets. Next, the clamp body is pushed against the outermost sheet S (position of Fig. 2), in which position the outer ends of the fingers and the central spreader arm 40a project through the perforations. Then the spring is released and acts to retract the fingers 19 until the shoulders 28 abut the sheet farthest from the clamp, the sheets S being resiliently clamped between said shoulders and the spherical sheet engaging surface 35b of the insulator (position of Fig. 3). To remove the clamp, the spring is again compressed so that the fingers are protracted sufficiently to enable the enlarged ends 27 to be compressed towards each other and withdrawn through the perforations.

In Fig. 7, I show a modified form of my clamp in which the parts are as before described and are given like numerals, except that the cross arm 40 of the spreader is relatively longer and its outer end portions fit into transverse slots 50 provided in flange 35a of the insulator 35. Thus in this form of my clamp the spreader is not rotatable relative to the insulator. The insulator, however, is rotatable with respect to the body 5 and the cap 31.

While I have resorted to considerable detail for the purpose of making my invention understood, I wish it understood that within the broader scope of my invention, as defined by the appended claims, various modifications and adaptations may be made without departing from the spirit of the invention.

I claim:

1. A clamp for temporarily holding perforated sheets in superposed relation, including a body having a sheet-engaging end portion and a retaining member reciprocally mounted in the body and comprising a stem portion and a plurality of expansible fingers slidable through said end portion to clamp said sheets towards said sheet-engaging end portion, said fingers having inner end portions embracing the stem exterior.
2. A clamp for temporarily holding perforated metal sheets in superposed relation, comprising: a body having a substantially non-yielding plastic sheet-engaging end cap and a retaining member slidably mounted in and projectable from the body, said retaining member embodying means for clamping said engaged sheet against said end cap.
3. A clamp for temporarily holding perforated sheets in superposed relation, comprising: a body having a substantially non-yielding plastic sheet-engaging end portion, a retaining member reciprocally mounted in the body and having a sheet-engaging portion, and spring means mounted in the body and operatively engaging the retaining member whereby to resiliently clamp said sheets between the sheet-engaging portion of the retaining member and said plastic sheet-engaging end portion of the body.
4. A clamp for temporarily holding perforated sheets in superposed relation, comprising: a cylindric body having an end wall presenting a central opening, an elongated retaining member reciprocally mounted in the body and having diametrically expandable prongs projectable through said opening whereby to be inserted through said perforations, a spreader disposed between said prongs for expanding them into engagement with the side walls of the perforations, said spreader having an inner anchor portion disposed against the outer surface of the end wall, means for securing said spreader against escape from the body including an end cap secured over the end wall, an enlarged central opening through said cap, an insulator overlying said anchor portion and having an annular flange confined between the cap and said end wall and a medial portion projecting through said enlarged central opening, said medial portion presenting towards said sheets a convexed relatively non-abrasive sheet-engaging portion, and resilient means carried by the body and retractably engaging said retaining member whereby to clamp said engaged sheet against said convexed sheet-engaging portion.
5. A clamp for temporarily holding perforated sheets in superposed relation, comprising: a cylindric body, a retaining member reciprocally mounted therein, said member including a stem and clamping fingers projectable at their outer ends from the housing for insertion through perforations in the sheets, the inner ends of said fingers having bifurcated portions embracing the stem, and means resiliently urging the retaining member into clamping position consisting of a coil spring longitudinally encircling the stem, said spring engaging said fingers whereby to hold them in position embracing the stem.
6. A clamp for temporarily holding perforated sheets in superposed relation, comprising: a cylindric body, a retaining member reciprocally mounted therein, said member including a stem extending at its inner end into the body, an annular groove between the ends of the stem,

clamping fingers projectable at their outer ends from the housing, each of said fingers having a bifurcated inner end portion disposed at right angles to the longitudinal axis of the stem and engaging circumferentially in said groove to prevent longitudinal movement of the fingers relative to the stem, and a coil spring mounted in the housing coaxially of the retaining member, said spring confining said inner end portions of the fingers against lateral escape from the groove.

7. In a clamping device for holding perforated sheets in superposed relation, a body, a retaining member movably mounted in the body, said retaining member comprising an operating stem, a spring bearing against the stem, and a clamping element held in detachable engagement with the stem by the spring.

8. In a clamping device for holding perforated sheets in superposed relation, a body, a retaining member movably mounted in the body, said retaining member presenting radially expansible sheet clamping segments projectable through an end of the body, an expander disposed between said segments, an end member rotatably disposed over said end of the body, said end member presenting an outer sheet engaging surface which is non-abrasive with respect to the engaged sheets and a central hole passing said

segments, a transverse slot in the inner face of the end member, said expander having an anchor portion engaging in said slot whereby to be non-rotatable with respect to the end member, and a ring secured to said end of the body in position circumferentially embracing the end member, said end member being rotatable with respect to the ring.

9. A clamp for temporarily holding perforated sheets in superposed relation, including a body having a sheet-engaging end portion and a retaining member reciprocally mounted in the body and comprising a stem portion and a plurality of expansible fingers slidable through said end portion to clamp said sheets towards said sheet-engaging end portion, each of said fingers having a lateral projection embracing the stem exterior, and means preventing relative longitudinal movement of said fingers with respect to the stem.

10. A clamp for temporarily holding perforated metal sheets in superposed relation, comprising: a body having a substantially non-deformable plastic sheet-engaging end member and a retaining member slidably mounted in and projectable from the body through said end member, said end member presenting a spherical sheet-engaging surface.
